ATTORNEY

UNITED STATES PATENT OFFICE.

FRANK STEAD, OF PROVIDENCE, RHODE ISLAND.

LOOM-REED.

1,258,494.

Specification of Letters Patent.

Patented Mar. 5, 1918.

Application filed July 7, 1917. Serial No. 179,145.

To all whom it may concern:

Be it known that I, FRANK STEAD, a citizen of the United States, and resident of the city of Providence, in the county of Providence and State of Rhode Island, have invented certain new and useful Improvements in Loom-Reeds, of which the following is a specification.

This invention relates to end bars for 10 reeds, and has for its object to provide such a bar which is formed of sheet metal folded longitudinally into trough-shape of a width to fit the space between the side ribs on the reed, means being provided at the end of 15 each bar for connecting them to the ends of the ribs.

With these and other objects in view, the invention consists of certain novel features of construction, as will be more fully described, and particularly pointed out in the appended claims.

In the accompanying drawings:

Figure 1— is a perspective view showing the end portion of a reed with my improved 25 end bar connected thereto.

Fig. 2— is a perspective view of the bar looking at its inner edge.

Fig. 3— is a view of one end portion of 30 the bar showing its oppositely disposed loops as embracing the side ribs of the reed.

Fig. 4— is a top view showing the bar as connected to the end of a reed and showing the loops of the bar as partly broken away.

Fig. 5— is a perspective view showing a 35 portion of a reed with the end bar removed showing the ends of the side ribs.

Fig. 6— is a view showing the shape of the metal at the ends of the bar as blanked from sheet stock.

40 Referring to the drawings, 10 designates a loom reed which is constructed in the usual way with the ends of the dents 11 secured between the half-round wooden strips or ribs 12, the ends of which ribs extend out beyond 45 the dents as illustrated in Fig. 5 and have a space 13 between them.

My invention provides end bars 14 for the reed, each of which is constructed of sheet metal which is first blanked from sheet stock 50 in the form illustrated in Fig. 6 in which the ends are slotted as at 18 providing end portions 19 subsequently bent to form the loops presently described. The body portion is then folded longitudinally into trough- 55 shape as best illustrated in Fig. 2, the width of the bar when finished being equal to the

space 13 between the ribs it is to fit, thereby providing a bar which is very strong in construction and extremely light in weight, which will take the place of the heavy solid 60 bar ordinarily employed for this purpose. The ends 19 of the side walls of this bar which extend beyond the bridge portion 15 thereof are bent outwardly into oppositely disposed loops 16 of a shape and size to receive and inclose the ends 12 of the side ribs. 65

When this bar so constructed is positioned on the end of the reed, these loops 16 take the place of end caps which are usually employed for securing the old style solid bar in 70 position.

Upon positioning my improved end bar on the reed it is only necessary to drive a staple 17 over the bridge portion into the wooden ribs thus securely fastening this bar against 75 displacement.

By the use of my improved sheet metal end-bar on reeds of this character I first do away with the comparatively expensive brass caps which are usually employed for 80 locking the ends of the solid end-bar; second, I provide a bar which is lighter in weight and therefore, cheaper in construction than the solid end bar, as the labor of bending the metal is less than the difference 85 in the cost of the heavier materials; third, the end-bar is made up of a single piece of metal and may be applied to a reed by a single operation.

The foregoing description is directed 90 solely toward the construction illustrated, but I desire it to be understood that I reserve the privilege of resorting to all the mechanical changes to which the device is susceptible, the invention being defined and 95 limited only by the terms of the appended claims.

I claim:

1. In a loom reed dent-supporting side ribs spaced apart at their ends, and an end-bar formed of sheet metal folded longitudinally to form an elongated trough of a width to fit the space between said ribs, and means at the ends of said bar for connecting them to the ends of said ribs. 100

2. In a loom reed, dent-supporting side ribs spaced apart at their ends, an end-bar formed of sheet metal folded longitudinally into trough-shape of a width to fit the space between said ribs, the stock at the ends of 110 said bar being folded to engage the ends of said ribs.

3. In a loom reed, dent-supporting side ribs spaced apart at their ends, an end-bar formed of sheet metal folded longitudinally into trough shape of a width to fit the space between said ribs, the stock at the ends of said bar being provided with extending side portions bent into oppositely disposed loops to engage the ends of said ribs, and means

for preventing said loops from being withdrawn from said ribs.

In testimony whereof I affix my signature in presence of a witness.

FRANK STEAD.

Witness:

HOWARD E. BARLOW.
